UNITED STATES PATENT OFFICE.

ISAAC FALK, OF NEW YORK, N. Y.

PUSH-PIN.

1,066,095.

Specification of Letters Patent.

Patented July 1, 1913.

Application filed August 16, 1912. Serial No. 715,369.

To all whom it may concern:

Be it known that I, ISAAC FALK, residing at New York, in the county of New York and State of New York, have invented certain new and useful Improvements in Push-Pins, of which the following is a specification.

This invention relates to an improved form of push-pin, and the object thereof is 10 to provide a push-pin, or tack, suitable for use wherever such articles are desirable, as, for instance, in the adjustment and support of draperies, and the like, for the use of draftsmen, etc., and to cheapen the manufacture thereof, and at the same time provide a thoroughly practical and satisfactory article.

A further object is to provide a push pin of such construction that all possibility of the 20 upper end of the shank of the pin being forced through the head, to the discomfort of the user, is avoided.

A further object is to provide a push pin comprising a severed length of wire bent 25 to form a shank and a head, and to arrange the shank so as to support the head at a locality spaced from the point where it merges into the head.

A further object is to provide a head of 30 convolute formation, and to so arrange the convolutions that they will serve to support each other against the pressure exerted by the user.

Other objects and aims of the invention, 35 more or less specific than those referred to above, will be in part obvious and in part pointed out in the course of the following description of the elements, combinations, arrangements of parts and applications of 40 principles, constituting the invention; and the scope of protection contemplated will be indicated in the appended claims.

In the accompanying drawings which are 45 to be taken as a part of this specification, and in which I have shown a merely preferred form of embodiment of the invention; Figure 1 is a transverse, vertical, sectional view through a pin formed in accordance with this invention, the section being taken substantially on the plane of line I—I of Fig. 2; Fig. 2 is a top plan view of the pin shown in Fig. 1; Fig. 3 is a transverse, vertical, fragmentary, sectional view, on a reduced scale, illustrating a means for altering 50 the cross-sectional contour of the several convolutions comprising the head of the pin,

whereby said convolutions are more positively supported by each other and a more uniform appearance given to the finished article, the view illustrating in dotted lines 60 the original position and shape of the several convolutions of the head before the altering process was begun; and Figs. 4, 5 and 6 illustrate modifications.

Referring to the drawings by numerals, 65 and particularly to Figs. 1 and 2, the numeral 1 indicates the shank of the pin, and 2, the tapered, or pointed, end thereof. The whole pin comprises preferably a single severed length of wire bent abruptly at the 70 upper end of the shank, as at 3, and formed into closely wound convolutions encircling the upper bent portion 3 of the shank, so as to form the head 4. There may, of course, be made as many convolutions as desired, 75 though four only are illustrated. The innermost convolution 5 is preferably arranged so as to engage a relatively upper surface or shoulder, as 6, produced at the upper end of the shank 1 by the bend 3, the engagement 80 with said shoulder serving to positively support the inner convolution against movement downwardly along the shank, when the pin is being pushed by the user. In winding the successive convolutions 7 and 8 about the 85 convolution 5; the same are preferably so arranged that a portion of the material thereof continuously overlaps a portion of the material of the convolutions, already wound, as clearly shown in Fig. 1, and, by 90 dotted lines in Fig. 2, so that said lapping portions form positive resistance to movement of one convolution relatively to another when the pin is being pushed. This arrangement provides a substantially solid 95 central portion for the head, the relative size of which portion is obviously determined by the number of convolutions arranged in overlapping relation. In fact the whole head may be arranged in this 100 manner, if desired. Beyond these, more convolutions, as 9, may be added, in a common plane, if desired, for enlarging the head.

Since ordinary round wire is cheapest to 105 use for the making of these pins, it may be desirable after they are formed, as above described, to press the heads as illustrated in Fig. 3. This operation is, however, not essential to the production of a pin embodying the characteristics of this invention. The press illustrated comprises a bottom die

10 having a central aperture 11 for the reception of the shank of the pin, and preferably having its die surface formed so as to properly receive the convolutions of the head as illustrated, and another die 12 similarly formed. When the dies are brought into pressing relation, the wire, comprising the head of the pin, is mashed, or pressed, substantially into the cross-sectional contours illustrated in this figure, their original position, and the fact that the outer dimensions of the head are limited by portions 13 of the die 12, serving to form the several cross-sectional contours so as to provide the 15 relatively inclined contacting surfaces 14, which serve to prevent movement of one convolution relatively to the other in one direction.

It will be noted that in the structure of 20 Fig. 1 the outer edge of the pin is removed from the transverse plane of the inner surface of the bend 3 so that the outer annular portion of the pin could not possibly come into holding contact with an article to be held. Since this fact may be objectionable for some purposes, it is, of course, within the province of this invention to form the head as shown in Fig. 4, wherein, all of the several convolutions thereof are arranged in 30 a common plane, so that the under side of the head forms a holding surface throughout its extent. The inner convolution 5 in this modification, preferably engages the shoulder portion 6, of the shank, as in Fig. 35 1, though this engagement may be eliminated, if desired. In this modification the several convolutions are obviously capable only of supporting one another through the action of such friction as may be present 40 between the contacting surfaces. The wire from which the pin is fashioned should, therefore, preferably be of a somewhat heavier quality than in the structure Fig. 1.

In Fig. 5 a pin is illustrated constructed 45 in all respects similar to that shown in Fig. 1, but being provided with an additional convolution as 15 disposed so that its under surface lies in a plane common with, or preferably slightly below, the plane of the under 50 surface of the bent portion 3 of the shank. This additional convolution forms a holding rim upon the pin such as will engage a surface into which the pin is pushed.

In Fig. 6 there is illustrated a pin formed 55 of a wire which, though slightly more expensive to manufacture, produces a pin having a substantially solid head. The cross-sectional contour of this wire is preferably such as to provide a groove 16 extending along one side and a corresponding ridge 17 extending along its opposite side, so that when the wire is wound into convolutions, as shown, the groove 16 of each convolution will engage over the juxtaposed 60 ridge 17 of the next succeeding convolution,

and these overlapping portions, in the completed article, will positively hold the several convolutions against movement relatively to each other in both directions longitudinally of the shank 1. The shoulder 70 6 performs the same function in this modification as heretofore, and, making the first or innermost convolution rigid, provides a substantial support for positively supporting the head as a whole. With this or similar specially shaped wire, the head of the pin may be made substantially flat as illustrated, which structure is desirable in many instances.

As many changes could be made in the 80 above construction without departing from the scope of this invention, it is intended that all matter contained herein, or shown in the accompanying drawings, shall be interpreted as illustrative and not in a limiting sense, and that the language used in the following claims is intended to cover all of the generic and specific features of the invention as defined by the claims.

Having thus described my invention what 90 I claim as new and desire to secure by Letters Patent, is:

1. An article of the class described comprising a shank, and a head, the head being of convolute formation, and the shank having a part forming a shoulder for supporting one of the convolutions of the head. 95

2. An article of the class described, comprising a shank, and a head, the head being of convolute formation, and the shank being formed integral therewith, and having a bent portion merging into the innermost convolution of the head, said bent portion being arranged to engage and support said innermost convolution at a point spaced 100 from the point where it merges thereinto.

3. An article of the class described, formed of a severed length of wire bent to provide a shank and a head, the head comprising a series of interlocking convolutions encircling one end of the shank. 110

4. An article of the class described, formed of a severed length of wire bent to provide a shank and a head, the head comprising a series of transversely lapping convolutions 115 encircling one end of the shank.

5. An article of the class described, having a shank and being formed with a head comprising a series of interlocking convolutions. 120

6. An article of the class described, having a shank and being formed with a head comprising a series of transversely lapping convolutions.

7. An article of the class described, formed 125 with a head comprising a series of convolutions arranged to support each other, and a shank extending beneath and supporting one of said convolutions.

8. An article of the class described hav- 130

ing a shank and having a substantially rigid head formed of a series of convolutions, one of said convolutions being formed with a transversely projecting part arranged for 5 supporting another of said convolutions.

9. An article of the class described, having a shank and being formed with a head comprising a continuous length of material bent to form a series of convolutions, and 10 said convolutions being arranged to support each other independently of their continuous formation.

10. An article of the class described, hav-

ing a shank and having a substantially rigid head formed of a series of convolutions, the 15 relatively inner convolutions having transversely projecting parts adapted to support the relatively outer convolutions which encircle them.

In testimony whereof I affix my signature 20 in the presence of two witnesses.

ISAAC FALK.
